W. BAYLEY.

WINDOW SCREEN FOR SWINGING SASHES.

APPLICATION FILED OCT. 23, 1913.

1,273,133.

Patented July 23, 1918.

UNITED STATES PATENT OFFICE.

WILLIAM BAYLEY, OF SPRINGFIELD, OHIO.

WINDOW-SCREEN FOR SWINGING SASHES.

1,273,133.

Specification of Letters Patent. Patented July 23, 1918.

Application filed October 23, 1913. Serial No. 796,812.

To all whom it may concern:

Be it known that I, WILLIAM BAYLEY, citizen of the United States, residing at Springfield, in the county of Clark and State of Ohio, have invented certain new and useful Improvements in Window-Screens for Swinging Sashes, of which the following is a specification.

My invention relates to window constructions, of the swinging sash type and more particularly to the application of fly screens thereto.

The invention as herein shown and described is especially adapted to center pivoted swinging sash or to center pivoted ventilators and particularly to such ventilators as are found in large window units in factory and auditorium constructions.

It is desirable to provide fly screens for screening window openings, particularly in bakery, confectionery, auditorium, school and residential constructions. It has heretofore been the custom when attempting to screen a swinging sash window to construct a semicircular inclosure of screen material upon the exterior or interior of the window. Such arcuate screen inclosures are unsightly in appearance and occupy an excessive amount of space.

The object of the invention is to simplify the structure as well as the means and mode of operation of such devices, whereby they will not only be cheapened in construction, but will be more efficient in use capable of being easily and quickly adjusted, of a pleasing conventional appearance, so arranged as to obviate all interference between the swinging sash and the screen and unlikely to get out of repair.

A further object of the invention is to provide means whereby the screen will maintain constant engagement with the swinging sash in all its positions of angular adjustment.

With the above primary and other incidental objects in view as will more fully appear in the specification, the invention consists of the features of construction, the parts and combinations thereof and the mode of operation or their equivalents as herein-after described and set forth in the claims.

In the drawings, Figure 1 is a perspective view of a portion of a metallic window sash, such as is commonly used in factory or auditorium construction, having a center pivoted ventilator therein to which a fly

screen has been applied in accordance with the invention herein described and shown. Fig. 2 is a vertical sectional view of the swinging sash and window screen, the sash being shown in its closed position. Fig. 3 is a detail view of the central or engaging portion of the sash and screen, the sash being shown in its open position. Figs. 4, 5, 6, 7 and 8 are detail views of modification of the construction.

Like parts are indicated by similar characters of reference throughout the several views.

In the drawings, 1 is a portion of a window unit comprising angularly disposed sash bars 2, in which are secured panes of glass 3. The window unit shown is provided with a center pivoted swinging ventilator sash 4, capable of oscillatory movement about a transverse medially disposed axis. The swinging sash may be supported on any suitable form of trunnions. Such trunnion or pivotal support forms no part of the present invention, and therefore has not been illustrated in detail. The sash being centrally supported, its opposite ends swing to and from the top bar 5 and the sill bar 6 of the window opening.

In Figs. 2 and 3 of the drawing, the swinging sash has been shown provided with transversely disposed parallel sash bars 7, located adjacent to but on opposite sides of the axis of the swinging sash. Located intermediate the transverse sash bars 7 is a reversed channel bar 8 of substantially Z or S shaped cross sectional form.

The fly screen is divided into two separate sections, an upper section 9 upon one side of the swinging sash and a lower section 10 upon the opposite side thereof. These sash sections are so located in relation with the sash, that the latter in its opening movement will swing away from both screen sections. The screen sections 9 and 10 are permanently secured in their respective position.

Carried upon the adjacent edges of the respective screen section are flexible plates or flanges 11 projecting one toward the other and engaging the opposite sides of the reversed channel bar 8 adjacent to the axis of the sash as shown in Figs. 2 and 3. The construction is such that as the sash swings to its open position the flanges or plates 11 are flexed in opposite directions by the rotation of the reversed channel or Z bar. The

resiliency of the flexible flanges or plates 11 serves to maintain such plates in constant engagement with the reversed channel or Z bar throughout the full degree of the movement of the window sash. This effectually obviates any opening intermediate the sash and screen at any position in the path of travel of the former. As the sash is returned to its normal position, the flexible plates of the flanges 11 likewise assume their normal positions as shown in Fig. 2, meanwhile maintaining constant engagement with the sash.

In Fig. 4 there is shown a modification of the construction in which a pipe or transverse tubular member 12 is substituted for the Z bar 11. This tubular member is concentric with the axis of oscillation of the sash. The flexible plate or flanges 11 of the screen engage the periphery of the pipe or tubular member. Inasmuch as the tubular member 12 is concentric with the axis of oscillation, it will be noted that no flexing of the flanges or plates 11 will occur upon the oscillation of the sash. Constant engagement of the flanges or plates 11 with the pipe or tubular members 12 will be maintained by the resilience of the flanges throughout the full degree of adjustment of the sash to exclude insects and to prevent their entrance between the adjacent edges of the screen sections.

In Fig. 5 there is shown a construction similar to that of Fig. 3 except that in lieu of the flexible plate or flanges 11, carried by the screen section arcuate flanges 13 are provided upon the swinging sash. These arcuate flanges 13 are concentric with the axis of oscillation and of sufficient radius to insure their engagement with the adjacent edges of the sash sections throughout the movement of the sash as indicated by dotted lines.

It is obvious that in lieu of the arcuate flanges as shown in Fig. 5, the flanges 13 might be flexible and flat or tangential in relation with the axis of the sash, in which case such flanges would yield against the resiliency thereof as the sash is oscillated. Such construction is so obvious upon examination of Fig. 5, as to need no further illustration.

In Fig. 6 there is shown a modification of the construction disclosed in Figs. 2 and 3 differing therefrom only in the fact that the parallel sash bars indicated at 7 in Figs. 2 and 3 and the intermediate transverse bar 8 are formed integral one with the other, thus necessitating but a single piece or bar at the axis of the sash. The construction and operation is otherwise the same as that of Figs. 2 and 3.

In Fig. 7 there is shown a further modification embodying a single transverse sash bar 14 carrying at its opposite edges arcuate

flanges 15 concentric with the axis of oscillation and adapted to engage the edges of the adjacent screen sections. It is obvious that in lieu of the arcuate flanges 15 as shown, these flanges may be flat and flexible whereby they will yield to compensate for the adjustment of the sash.

In Fig. 8 is shown a further modification in which the opposite edges of the transverse sash bar are each provided with an in-turned arcuate flange 16 concentric with the axis of oscillation. These arcuate flanges 16 engage the adjacent screen sections throughout the full degree of movement of the sash. It is obvious that in lieu of locating the screen sections closely adjacent to the arcuate flanges 16 as shown in said Fig. 8, the screen sections may be spaced away therefrom and provided with flanges similar to the flanges 11 of Fig. 4, which will bear upon the arcuate surfaces of the flanges 16. Such construction is obvious in view of Fig. 4.

It will be noted that in each of the constructions referred to, there are provided two separated screen units located on opposite sides of the swinging sash and provided with means for maintaining constant engagement with the sash throughout all positions of angular adjustment thereof.

The sash construction embodying the parallel transverse sash bars located at opposite sides of the axial line of the sash as herein described, enables the screen flanges 11 to be carried into the body of the sash to a position closely adjacent to the axis of oscillation, thus not only improving the appearance of the construction, but enabling the sash to operate with minimum effort and with minimum flexing of the flanges.

While the sash herein shown and described is of the center pivoted, horizontal axis type, it is to be understood that the invention is not limited to such construction. The construction herein shown is equally applicable to a sash pivoted on a vertical axis or to a single leaf sash pivoted adjacent to the edge thereof. In the latter case only a single screen section will be employed.

From the above description it will be apparent that there is thus provided a device of the character described, possessing the particular features of advantage before enumerated as desirable but which obviously is susceptible of modification in its form, proportion detail construction or arrangement of parts, without departing from the principle involved or sacrificing any of its advantages.

While in order to comply with the statute, the invention has been described in language more or less specific as to certain structural features, it is to be understood that the invention is not limited to any specific details, but that the means and construction herein

described comprise but one mode of putting the invention into effect and the invention is claimed broadly in any of its possible forms or modifications within the scope of 5 the appended claims.

Having thus described my invention, I claim:

1. A swinging sash, having a transverse recess therein adjacent to the axis of oscillation, and a screen section to and from which the sash swings projecting within the transverse recess.
- 10 2. In a screen construction for swinging sash windows, a swinging sash, a reversed channel bar carried by the sash in a position in axial alignment therewith, a screen section to and from which the sash is oscillated, and a flexible flange carried by the screen and yieldingly engaging the reversed channel 20 bar.
- 15 3. In a screen construction for swinging sash windows, a center pivoted sash, two screen sections located in substantially parallel planes one at the inside and one at the outside of the window space and at opposite sides of the pivotal center of the sash to and from which the corresponding leaves of the sash are oscillated, a substantially Z shaped contact bar carried by the sash adjacent to 25 the axis of oscillation thereof, and flexible tensioned flanges carried by the screen sections engaging the opposite sides of the bar.
- 30 4. In a window of the character described, the combination of a window casing, a pivoted tilting sash, a lower screen secured to

said window casing inside of said sash and below the pivoting points thereof, a filling strip secured to the sash substantially in line with the pivoting points and making a close joint with the top element of said 40 screen, said filling strip having an angular recess for continuously engaging the upper portion of said element.

5. In a window construction as described, a swinging window sash having parallel 45 transverse bars located adjacent to but on opposite sides of the axis of oscillation, screen sections located at opposite sides of the swinging sash, and flanges extending between the parallel sash bars and forming 50 closures between the sash and adjacent screen sections.

6. In a construction of the character described, the combination of a window casing, a pivoted tilting sash having pivoting points 55 in the plane of the sash, a lower screen secured to said window casing inside of said sash and below the pivoting points thereof, a filling strip secured to the sash substantially in line with the pivoting points, a 60 connecting strip secured to the upper end of the screen and making a tight joint with said filling strip.

In testimony whereof, I have hereunto set my hand this 8th day of October, 1913.

WILLIAM BAYLEY.
